UNITED STATES PATENT OFFICE.

ALEXANDER ANDERSON, OF CHICAGO, ILLINOIS, ASSIGNOR TO HARRY H. BECKWITH, OF BOSTON, MASSACHUSETTS.

APPARATUS FOR SOFTENING PARTS OF ASSEMBLED UNLASTED SHOE-UPPERS.

1,132,645.

Specification of Letters Patent. Patented Mar. 23, 1915.

Application filed April 18, 1914. Serial No. 832,763.

To all whom it may concern:

Be it known that I, ALEXANDER ANDERSON, a citizen of the United States, and a resident of the city of Chicago, in the county 5 of Cook and State of Illinois, have invented certain new and useful Improvements in Apparatus for Softening Parts of Assembled Unlasted Shoe-Uppers, of which the following is a specification.

10 In the manufacture of shoes having stiffened toe portions, it is now customary to assemble the parts of the upper and temporarily engage them by means of a tack with the heel end of a last, said parts including the usual vamp, the quarters, the 15 lining, the toe cap, and a flat box toe blank secured to the forward end of the vamp and interposed between the lining and the toe cap. The box toe blank is usually made of 20 felt, treated with a composition which is adapted to be quickly softened by heat to render the blank limp and pliable, and to harden by cooling to make permanent the 25 form imparted to the blank by the toe portion of the last during the lasting operation.

My invention is embodied in an apparatus, comprising a receptacle having an opening for the reception of a flat box toe blank 30 provided with a stiffening composition and means for supplying hot vapor within the receptacle to soften the blank preparatory to lasting, an open recess being provided adjacent said opening for the reception of 35 the toe portion of a last engaged with the assembled and unlasted parts of a shoe upper which includes said blank, the said apparatus being adapted to soften the blank while the upper, of which it forms a part, 40 is engaged with the heel end of the last so that the softened blank and the portions of the upper between which it is interposed may be immediately conformed to the toe 45 portion of the last without disengaging the upper from the last.

The invention also includes means for supporting the unlasted toe cap out of contact with the box toe blank during the softening operation.

50 Of the accompanying drawings, forming a part of this specification, Figure 1 represents a perspective view of an apparatus embodying my invention. Fig. 2 represents a transverse section of said apparatus and a 55 side view of a last and an unlasted upper

engaged with the heel end thereof, said last and upper being presented to the apparatus with the blank inserted in said receptacle, the toe portion of the last and the corresponding portion of the lining being inserted in the recess at one side of the receptacle and the toe cap being held out of contact with the blank. 60

The same reference characters indicate the same or similar parts in all of the views. 65

In the drawings, 12 represents a last, to the heel end of which is temporarily secured by a tack 13 a heel portion of an unlasted upper, said upper including the usual vamp 14, lining 15, toe cap 16, and box toe blank 17. The blank 17 is or may be a flat piece of felt treated with a composition adapted to be softened by heat and rendered hard by cooling, one edge of the blank being preferably attached as usual to the forward edge 75 of the vamp 14.

The apparatus of my invention is an elongated structure, preferably of sheet metal, having end walls 19, a back wall 20, a top wall 21, a front wall 22 and a bottom wall 80 23. A recess 24 is provided below the bottom wall 23 for the reception of the toe portion of the last and the corresponding portion of the lining 15, said recess being preferably formed by extensions of the end walls 85 19, a downwardly projecting extension of the bottom wall 23, and a shelf 25 attached to the end wall and bottom wall extensions. The continuity of the front wall 22 is interrupted to form an opening 26 closely adjacent to the recess 24, said opening being 90 adapted to receive the box toe blank 17.

Means are provided for supplying a heating agent within the receptacle, said agent being preferably low-pressure steam or 95 vapor introduced through a supply pipe 27, and a branch pipe 28 communicating therewith and extending lengthwise of the receptacle, said pipe having perforations 29 of suitable size and suitably spaced apart to 100 distribute steam or vapor through the interior of the receptacle.

The portion of the front wall 22 adjacent to the opening 26 constitutes a means for supporting the toe cap 16 out of contact 105 with the blank 17, as indicated by Fig. 2, so that the blank is exposed to the heating agent circulating within the receptacle. A flange 30 is extended inwardly from the front wall 22 over the recess 26, said flange 110

constituting a baffle which prevents the heating agent circulating in the upper forward portion of the receptacle from passing directly outward through the opening 26.

5 The bottom wall 23 is preferably inclined downwardly from its forward or outer edge, as shown by Fig. 2, so that water of condensation accumulating thereon is conducted rearwardly to the back part of the receptacle from which it may escape through an outlet pipe 31.

10 The above described structure may be attached to a bench 32 or other suitable support.

15 It will now be seen that a last, to the heel portion of which the assembled parts of an unlasted upper is temporarily attached, may be presented to the apparatus in the manner indicated by Fig. 2, the box toe blank being allowed to remain in the opening 26 until it has become suitably softened. The last and the upper thereon is then removed from the apparatus and the upper is lasted while the box toe blank is soft, the 20 subsequent stiffening of the composition with which the blank was treated making the form of the lasted toe portion of the upper permanent. The apparatus is preferably elongated so that several lasts and 25 the uppers engaged therewith may be presented to the apparatus simultaneously.

I claim:

30 1. An apparatus of the character described comprising a receptacle having an opening for the reception of a flat box toe blank, and means for supplying a heating agent within the receptacle to act on said blank, the apparatus being provided with an open recess adjacent to said opening for the reception of the toe portion of a last engaged with the assembled and unlasted parts of a shoe upper which includes said blank.

35 2. An apparatus of the character described comprising a receptacle having an opening for the reception of a flat box toe blank, means being provided for supporting an unlasted toe cap out of contact with said blank, and means for supplying a heating agent within the receptacle to act on said blank, the apparatus being further provided with an open recess adjacent to said opening for the reception of the toe portion of a last engaged with the assembled and 40 unlasted parts of a shoe upper which includes said blank and toe cap.

45 3. An apparatus of the character described comprising a receptacle having an opening for the reception of a flat box toe blank, supporting means forming with a 50 portion of said receptacle, an open recess at

one edge of said opening for the reception of the toe portion of a last supporting the assembled and unlasted parts of a shoe upper which includes said blank, and means for supplying a heating agent within the receptacle to act on said blank.

4. An apparatus of the character described comprising a receptacle having an opening for the reception of a flat box toe blank, supporting means forming with a portion of said receptacle, an open recess at one edge of said opening for the reception of the toe portion of a last supporting the assembled and unlasted parts of a shoe upper which includes said blank, and means for supplying a heating agent within the receptacle to act on said blank, the wall of the receptacle at the opposite edge of said opening being arranged to support the unlasted toe cap, forming a part of said upper, out of contact with said blank.

5. An apparatus of the character described comprising a receptacle having an opening for the reception of a flat box toe blank, means for supplying a heating agent within the receptacle to act on said blank, the bottom of the receptacle being inclined to conduct water of condensation rearwardly from said opening, and supporting means holding said bottom in a raised position to form a recess for the reception of the toe portion of a last supporting the assembled and unlasted parts of a shoe upper.

6. An apparatus of the character described comprising a receptacle having an opening for the reception of a flat box toe blank, means for supplying a heating agent within the receptacle to act on said blank, supporting means holding said bottom in a raised position to form a recess for the reception of the toe portion of a last supporting the assembled and unlasted parts of a shoe upper, and a last-supporting shelf below said recess.

7. An apparatus of the character described comprising a receptacle having an opening for the reception of a flat box toe blank, means for supplying a heating agent within the receptacle, the apparatus being provided with a recess at one side of said opening for the reception of the toe portion of a last, and a baffle at the opposite side of said opening.

In testimony whereof I have affixed my signature, in presence of two witnesses.

ALEXANDER ANDERSON.
